UNITED STATES PATENT OFFICE.

WILLIAM W. TRINKS, OF BRIDGEPORT, CONNECTICUT, AND BENJAMIN W. TUCKER, OF SOUTH ORANGE, NEW JERSEY, ASSIGNEES TO PULLCLEAN MANUFACTURING CORPORATION, OF BRIDGEPORT, CONNECTICUT, A CORPORATION OF DELAWARE.

TOWEL-SEPARATING MECHANISM FOR LAUNDERING MACHINES.

Application filed May 5, 1924. Serial No. 711,131.

To all whom it may concern:

Be it known that we, WILLIAM W. TRINKS and BENJAMIN W. TUCKER, citizens of the United States, and residents, respectively, of 5 Bridgeport, in the county of Fairfield and State of Connecticut, and South Orange, in the county of Essex and State of New Jersey, have invented a new and useful Towel-Separating Mechanism for Laundering Machines; and we do hereby declare the following to be a full, clear, and exact description of the invention, such as will enable others skilled in the art to which it appertains to make and use the same.

15 In one type of towel cabinets now in quite general use the towel is rolled on a mandrel from which it is drawn in successive lengths as required for use, and, as the successive lengths are drawn from the cabinet, 20 the preceding soiled lengths are automatically wound about a second mandrel in the cabinet. Thus the towel is in roll form both when placed in the cabinet clean and when removed therefrom soiled.

25 A machine for laundering such rolled towels is disclosed in a co-pending application, Serial No. 516,806, filed November 21, 1921, the same comprising a washing means, a feeding means for unwinding the rolled 30 towel and carrying the same through said washing means, and winding means for receiving the laundered towel from the feeding means and automatically re-winding the same into roll form ready for use again in 35 the cabinet.

Because of the towels being in roll form when taken from the cabinet and during the subsequent manual handling of the same, it is obvious that damaged or torn towels are 40 not readily detected. It has therefore been the main object of our present invention to provide a simple and efficient means for separating torn from untorn towels. This we accomplish by equipping the laundering machine of our aforesaid application with 45 means which is operative, through engagement with the towels when being drawn through the machine in a flat or unrolled condition, to detect torn towels and subsequently separate the same after being rolled up from the untorn ones.

Our invention in one form thereof com-

prises a deflector located at the rear of the winding mechanism for movement to and from a position across the normal path of 55 the towels as they are discharged from the winding mechanism, a latch for normally holding the deflector in inoperative position, and rotatably mounted detector members located in advance of the winding mechanism 60 in yielding engagement with the unrolled towels whereby they will be caught in any opening or tear in a passing towel and rotated by the latter, which rotation of the detectors will act through suitable connections to release the latch from the deflector 65 and effect a movement of the latter to operative position to deflect the torn towel from its normal path of discharge, following 70 which the deflector will be automatically returned to its normal inoperative position so as not to interfere with the normal passage of the untorn towels.

Referring now to the accompanying 75 drawings,

Figure 1 is a side elevation of that part of the machine of our aforesaid application which is provided with the winding mechanism, the same also being here equipped with the torn towel detecting and separating mechanism of the present invention.

Fig. 2 is a top plan of part of the machine shown in Fig. 1 with the mandrel supporting and feeding devices of the winding mechanism removed.

Fig. 3 is a side elevation of that part of the machine shown in Fig. 2 with one of the side frames partly broken away.

Fig. 4 is an enlarged detail in side elevation of the torn towel detecting mechanism 90 at the front end of the winding mechanism, and

Fig. 5 is an enlarged detail in side elevation of the torn towel deflector and its latching mechanism which is located at the rear 95 of the winding mechanism.

Similar reference characters indicate like parts in the several figures of the drawings.

In the machine of our aforesaid application, the towels are adapted to be fed 100 through the laundering machine proper by a pair of endless carrier belts which loosely connect with the opposite ends of a bar that is passed through a loop in the leading end

of the towels. After being fed beyond the laundering machine proper, the bar in the leading end of the towels is taken from the main carrier belts by a second pair of feed belts which latter delivers said bar with the connected towel to a winding mechanism which winds up the laundered towels and discharges them from the rear end of the machine in roll form.

10. The main carrier belts referred to are in the form of sprocket chains mounted on suitably arranged pairs of guiding and operating sprocket wheels, such belts in the present case being diagrammatically indicated by the broken lines 53 and certain pairs of the sprocket wheels being indicated at 145, 146, 147, 148 and 149, the wheels 147 being mounted on a shaft 150 which is driven from a main drive shaft 10 at the side of the machine through bevel gearing 151.

The second pair of feed belts, termed the "releasing" belts and diagrammatically shown by the broken lines 220, are also in the form of endless sprocket chains which are mounted on pairs of sprocket wheels 221, 222, and 223, the first two pair being guide wheels and the last pair, those indicated at 223, being drive wheels and mounted on an intermittently operated clutch-controlled shaft 176. These feed belts 220, which are operated to move at a greater speed than that of the main carrier belts, are provided with projections 224 which are moved in paths to engage the ends of the towel bar 55 adjacent the rear end of the upper run of the main feed belts 53 and release said bar from the latter and deliver it to the towel winding mechanism.

40. The towel winding mechanism here shown is the same as that fully illustrated and described in our aforesaid application, but as the same acts to some extent in cooperation with the torn towel detecting and separating mechanism of the instant invention, we will briefly describe the same here. This winding mechanism comprises a plurality of endless belts 160 which are mounted on a series of sets of pulleys, such as indicated at 161, 162, 163, 164 and 165, certain of which are adjustable relatively to the others to permit of the upper run of belt between the pulleys 162 and 163 being placed in loop form whereby to provide a pocket 55 to receive and hold a hollow tube or mandrel 166 about which the towel is to be wound, the winding operation being performed by the running of the belts which act through frictional engagement with the tube or mandrel to revolve the same and thereby effect a winding of the towel thereon as the leading end of the towel is fed to said tube in the loop of the winding belts. The latter are operated to run continuously, the same being driven from the pulleys 162 which are

fixed to a shaft 167 driven from the shaft 150 through suitable gearing.

The tube holding loop or pocket in the upper run of the belts is formed at a predetermined time in the operation of the machine, to wit, just prior to the leading end of the towel reaching the belts, by the action of a plunger *p* which releases a tube from its containing magazine 190 to permit it to drop onto the upper run of belts, which at such time is in the straight dotted line position *a* of Fig. 1, after which, by a continued downward movement against the tube, the plunger depresses both said tube and the upper run of belts downwardly between the adjacent sets of pulleys 162 and 163. When the tube is thus pressed downward by the plunger *p* against the upper run of belts to form a loop therein, the pulleys 163 are at the same time moved forward towards the adjacent pulleys 162, as from the dotted line position *b* shown in Fig. 1 to the full line position shown, in order to cause the belts to closely embrace the tube and thereby more effectively assure the winding of the towel thereon when its leading end is moved into said loop of the winding belts by the carrier belts 220. As the winding operation proceeds following the entry of the leading end of the towel into the winding loop and about the tube therein, the diameter of the rolled towel of course gradually increases, as shown in Fig. 1, thereby making it necessary that the size of the winding loop should correspondingly increase. To provide for such increase in the size of the winding loop by automatically acting means, the shaft carrying the pulleys 165 is mounted on lever arms 170 which are pivoted to the frame 171 and provided with attached weights 172. Such movable support for the pulleys 165 automatically permits of any necessary variation in the length of the belt loop while at the same time it maintains the belt under constant tension.

During the winding operation and until the completion of the same, the pulleys 163 and plunger *p* maintain the positions shown in Fig. 1, that is, the pulleys 163 remain in their forward position adjacent the pulleys 162 to close the mouth of the winding loop and the plunger remains in its lowered position opposite said mouth of the loop; in this way serving to hold the towel in the winding loop of the belts during the winding operation. After the winding operation has been completed the pulleys 163 are automatically thrown back and the plunger raised, to release the rolled up towel *t* and permit its discharge from the machine. Such operations of the pulleys 163 and plunger *p* are automatically controlled from the intermittently operated clutch controlled shaft 176 through suitable connections,

which it is not necessary to here describe for the proper understanding of the present invention, such connections and their operation being shown and described in detail in our aforesaid application to which reference may be had.

When the rolled up towels *t* are discharged from the winding mechanism, they will, in following their normal path of discharge, drop from the winding belts into a transversely arranged trough 2 through which passes a conveyor 3 for delivering the towels to a desired location.

In accordance with our present invention, as hereinbefore referred to, we locate a detecting mechanism in advance of the winding mechanism which is operated by the passing of torn towels to cause a deflector at the rear of the winding mechanism to engage such torn towels and separate the same from the un torn ones by deflecting them from their normal path, i. e. in the case here shown the path leading to the trough 2.

The deflector is here shown in the form of a tilting platform comprising a series of slats 5 fixed to a shaft 6 supported at its ends in journal blocks 7 on the side frames 140 in position whereby the platform may be tilted to and from a position with one end projecting into the path of the rolled towels as they are discharged from the winding belts, as shown by the dotted line position in Fig. 1, in which position it will receive a rolled towel thereon and deflect it from its normal path leading to the trough 2. When in such towel intercepting position, the platform is held in an inclined position sloping downwardly towards its rear end by the engagement of an arm 8 on the shaft 6 with a stationary stop pin 9 on the frame, whereby the towel received thereon will be caused to gravitate to the rear end of the platform and be discharged therefrom at a point distant from the normal point of discharge into the trough 2, as will be clear by reference to Fig. 1.

The deflector platform is normally held in the inoperative position shown by full lines in Figs. 1, 2 and 3, by means of a latch 11 pivotally supported on the frame at 12 engaging with a tooth 13 on a segment 14 fixed to the shaft 6, as shown in Fig. 3. In this position of the deflector the normal path of the towels from the winding mechanism to the trough 2 is left open and unobstructed. Upon the release of the deflector by the disengagement of the latch from the segment tooth 13, it is automatically thrown into operative towel deflecting position by a spring 15 which connects at one end with a pin 16 on the segment 14 and at its opposite end with a fixed pin 17 on the frame. Such release of the deflector by the latch is automatically effected only through the detecting means at the front of the winding

mechanism when this is brought into operation by the passing of torn towels as will now be described.

The detecting means in a preferred embodiment of the invention comprises a plurality of plural-armed members 20 rotatably mounted for independent rotation on a shaft 21 which is supported adjacent its opposite ends in the outer ends of two arms 22-22 fixed to a rock-shaft 23, which latter is 70 mounted in suitable journal blocks on the opposite side frames of the machine. The members 20 are adapted to be normally held with one arm thereof in yielding engagement with the passing towels, as shown in 80 Fig. 3, whereby one or more of the same will be caught in any opening or tear that might occur in a passing towel, and the member being so caught, will be partially rotated by the engaging towel as shown in Fig. 4; the 85 table 24 over which the towels pass beneath the members 20 being longitudinally slotted to permit of the rotation of the ends of the arms of said members in a path beneath the top of the table as shown. Such rotation of 90 any one of the detector members 20, as effected by one of its arms being caught in an opening of a passing towel, acts to bring another of its arms into engagement with the oppositely located arm 25 on a rock-shaft 95 26 journaled in blocks 27-27 on the opposite side frames of the machine (Fig. 2) and effect a rocking of said shaft, which action of the latter is operative through suitable connections to release the latch 11 from 100 latching engagement with the segment 14 whereby the deflector may be thrown into operative position under the action of the spring 15 to intercept such torn towel as it is discharged from the winding mechanism 105 and deflect it from its normal path so as to separate the same from the un torn towels. The said connections between the rock-shaft 26 and latch 11 comprise a short lever arm 110 30 on the rock-shaft connecting through a long link 31 with a second lever arm 32 fixed to the latch.

When a detector member has been rotated by an engaging towel sufficiently far to release its arm from engagement with the 115 cooperating rocker-arm 25, the latter and associated rock-shaft will return to their normal position under the action of a spring 33 connecting at one end with a fixed pin 34 on the frame and at its opposite end with a pin 35 on the latch arm 32. When these parts are thus moved under the action of the spring 33, the latch 11 is also thereby moved into yielding contact with the lower edge of the segment 14 whereby it 120 will be caused to snap into latching engagement with the segment tooth 13 upon the movement of the deflector platform to its normal inoperative position, as shown in Fig. 3. The deflector is preferably lim- 125 130

ited upon reaching the latter position by the engagement of its arm 8 with a second stop pin 36 on the frame.

As hereinbefore referred to, the detector members 20 are adapted to be normally held with one arm thereof in yielding contact with the passing towels, as shown in Fig. 3. This is effected by securing a cam disk 40 to each detector member and mounting on the shaft 23 a plurality of independently movable spring-pressed arms 41 carrying rollers 42 at their free ends in engagement with the cam disks 40. These latter, as here shown, have three peripheral notches or depressions corresponding in number with the detector arms and which notches are so positioned relative to the latter that when entered by the roller of a co-acting spring arm, the end of a corresponding detector arm will be held in position for engagement with a towel. Upon the partial rotation of a detector member as effected by the engagement therewith of a torn towel, the co-acting spring arm 41 will yield to permit of such rotation by riding up on the adjacent high part of the cam, as shown in Fig. 4. Thereafter, when the detector has been rotated sufficiently far by the engaging towel to move the high part of the cam past the engaging spring arm, the roller on the latter will be pressed down into the succeeding notch of the cam and so automatically bring the succeeding arm of the detector into engagement with the towel. This operation is repeated upon each partial rotation of the detector by an engaging torn towel. The yielding action of the arms 41 may be provided for in any suitable way. In the present case a series of coiled springs 43 are located on the shaft 23, each connected at one end with a collar 44 fixed to the shaft and at its opposite end connected to an adjacent arm 41, whereby each arm 45 will be capable of independent spring action.

It will of course be obvious that any desired number of detector members may be employed, this depending primarily on the width of the towels to be acted on. A number of them are desirable in any event so as to detect an opening or tear at any point in the width of the towels. If a tear is small, it may catch only one detector, but this will act to bring the deflector into operation in the same manner and quite as effectively as though the tear was large enough to catch and operate several of the detectors.

The detector members in their normal operative position for pressing engagement with the towels are in the path of the bar 55 in the leading end of the towels, and, if engaged by said bar, would bring the deflector into operation. To avoid this, the shaft 23, which carries at the free ends of

its arms 22—22 the shaft 21 and supported detector members, is rocked in timed relation with the movement of the towel feed belts 220 to raise the detector members above the path of the towel bar upon the approach of the latter, and, upon the passage of said bar, lower the members into engagement with the towel. The means for effecting such movement of the detector members through the rock-shaft 23, comprises an arm 50 fixed to the rear end of the shaft, a bar 51 connecting at one end with said arm and at its opposite or lower end being longitudinally slotted for sliding engagement with the shaft 176, and a grooved cam 52 on the shaft 176 engaging a roller 56 on the bar 51 (Fig. 4), said cam being formed to impart the described raising and lowering movements to the detector members through the intermediate connections.

The operation of the machine, briefly stated, is as follows: When the bar 55 in the leading end of a towel is brought by the main carrier belts 53 to the "releasing" belts 220, the latter, through the projections 224 thereon, engage said bar and carries the same with the connected towel over the table 24 to the winding mechanism. During such movement of the towel bar, the detector members are raised above the path of the latter to permit of its passage therebeneath and then lowered onto the towel. If such towel is undamaged, that is, if it has no tears or openings therein, it passes to the winding mechanism without effecting any operation of the detecting and separating mechanism, and, upon its discharge from the winding mechanism, drops into the trough 2 to be carried to the desired delivery point by the conveyor 3. If however a torn towel comes through and is taken by the feed belts 220, the tear or tears therein will catch one or more of the detector members 20 and cause a partial rotation of the same, thereby bringing one of their arms into engagement with one of the arms 25 on the rock shaft 26 to rock the latter and thereby effect a release of the latch 11 from the segment 14 of the detector platform, whereupon the latter will be tilted under the action of the spring 15 from the inoperative position shown by full lines in Figs. 1 and 3, to its operative deflecting position shown by dotted lines in Fig. 1, in which latter position it will intercept and receive thereon said torn towel as it emerges in roll form from the winding mechanism. When the towel is thus received on the deflecting platform, it rolls to the rear end of the latter and thereby acts to reset the same in its normal inoperative position by bringing the locking tooth 13 on the segment 14 into locking engagement with the latch 11, as shown by dotted lines in Fig. 3. The mechanism

for detecting and separating torn towels is thus automatically operated and reset in the normal position by each torn towel as the latter passes through the machine. When 5 not operated by the passage through the machine of torn towels such mechanism remains inoperative.

What we claim is:

1. In a machine of the class described, the 10 combination with towel feeding means, of normally inoperative means for deflecting towels from their normal path, and means operated by the engagement of torn towels to bring the deflecting means into operation.
2. In a machine of the class described, the 15 combination with towel feeding means, of normally inoperative means for deflecting towels from their normal path, and means, including a detector member for engagement with the towels, operated through the engagement of torn towels with said member to bring the deflecting means into operation.
3. In a machine of the class described, the 20 combination with towel feeding means, of normally inoperative means for deflecting towels from their normal path, and means, including a yieldable detector member for engagement with the towels, operated through the engagement of torn towels with said member to bring the deflecting means into operation.
4. In a machine of the class described, the 25 combination with towel feeding means, of normally inoperative means for deflecting towels from their normal path, and means, including a plurality of detector members, operated through the engagement of torn towels with one or more of said members to bring the deflecting means into operation.
5. In a machine of the class described, the 30 combination with towel feeding means, of normally inoperative means for deflecting towels from their normal path, and means, including a rotatable detector member for engagement with the towels, operated through the engagement of torn towels with said member to bring the deflecting means into operation.
6. In a machine of the class described, the 35 combination with towel feeding means, of normally inoperative means for deflecting towels from their normal path, a detector positioned to enter an opening or tear in a passing towel and be actuated by the latter, and means operative upon the actuation of said detector to bring the deflecting means into operation.
7. In a machine of the class described, the 40 combination with towel feeding means, of normally inoperative means for deflecting towels from their normal path, a rotatable detector positioned to enter an opening or tear in a passing sheet and be rotated by the latter, and means operative upon the rotation of

of said detector to bring the deflecting means into operation.

8. In a machine of the class described, the combination with towel feeding means, of normally inoperative means for deflecting 70 towels from their normal path, a plurality of spaced detectors positioned to enter an opening or openings in a passing sheet and be actuated by the latter, and means operative upon the actuation of one or more of 75 said detectors to bring the deflecting means into operation.

9. In a machine of the class described, the combination with towel feeding means, of normally inoperative means for deflecting 80 towels from their normal path, a plurality of spaced independently acting detectors positioned to enter an opening or openings in a passing towel and be actuated by the latter, and means operative upon the actuation of one or more of 85 said detectors to bring the deflecting means into operation.

10. In a machine of the class described, the combination with towel feeding means, of normally inoperative means for deflecting 90 towels from their normal path, a rotatable detector positioned to enter an opening or tear in a passing towel and be rotated by the latter, means operative upon the rotation 95 of said detector to move the deflecting means to operative position, and means for bringing the detector to towel engaging position following its actuation by a passing towel.

11. In a machine of the class described, the combination with towel feeding means, of normally inoperative means for deflecting 100 towels from their normal path, a rotatable detector positioned to enter an opening or tear in a passing towel and be rotated by the latter, means operative upon the rotation 105 of said detector to move the deflecting means to operative position, and automatic means for bringing the detector to towel engaging position following its actuation by a 110 passing towel.

12. In a machine of the class described, the combination with towel feeding means, of normally inoperative means for deflecting 115 towels from their normal path, a rotatable detector positioned to enter an opening or tear in a passing towel and be rotated by the latter, means operative upon the rotation of said detector to move the deflecting means to operative position, and means for bringing the detector to towel engaging position 120 following its actuation by a passing towel, said last named means comprising a cam in fixed relation with the detector and a spring-pressed member co-acting with said cam.

13. In a machine of the class described, the combination with towel feeding means, of normally inoperative means for deflecting 125 towels from their normal path, a plurality of spaced independently acting rotatable detectors positioned to enter an opening or 130

- openings in a passing towel and be actuated by the latter, means operative upon the rotation of one or more of said detectors to move the deflecting means to operative position, and independently acting means for rotating the detectors to towel engaging position following their actuation by a passing towel, said last named means comprising a cam in fixed relation with each detector and 10 a spring-pressed member co-acting with each cam.
14. In a machine of the class described, the combination with towel feeding means, of normally inoperative means for deflecting towels from their normal path, a rotatable plural-armed detector normally positioned with one arm thereof in yielding engagement with a passing towel to enter a tear or opening therein whereby actuation 15 of the detector will be effected, means operative upon the actuation of said detector to move the deflecting means to operative position, and means for repositioning the 20 detector with one of its arms in towel-engaging position following its actuation by a 25 passing towel.
15. In a machine of the class described, the combination with towel feeding means, of a normally inoperative deflector for deflecting towels from their normal path, means operated by the engagement of torn towels to bring the deflector into operative position, and automatic means operative to 30 reset the deflector in its inoperative position 35 upon the passing of a torn towel thereover.
16. In a machine of the class described, the combination with towel feeding means, of a normally inoperative pivoted deflector for deflecting towels from their normal 40 path, means operated by the engagement of torn towels to bring the deflector into operative position, and automatic means operative to 45 reset the deflector in its inoperative position upon the passing of a torn 50 towel thereover.
17. In a machine of the class described, the combination with towel feeding means, of a deflector for deflecting towels from their normal path, a latch normally holding 55 the deflector in inoperative position, means operated by the engagement of torn towels to effect release of the latch and the bringing of the deflector into operative position, and means for resetting the latch upon the 60 passage of a torn towel over the deflector.
18. In a machine of the class described, the combination with towel feeding means, of a pivoted deflector movable to and from 65 an operative position in the path of the towels to deflect towels from their normal path, a latch normally holding the deflector in inoperative position, means operated by the engagement of torn towels to effect release of the latch and the tilting of the 70 deflector into operative position, the said 75 deflector being tilted to inoperative position upon the passage of a torn towel thereover, and automatic means for resetting the latch upon said tilting of the deflector to inoperative position.
19. In a machine of the class described, the combination with means for feeding towels in flat form, of a pivoted deflector movable to and from an operative position in the path of the towels to deflect torn towels from their normal path, a latch normally holding the deflector in inoperative position, means operated by the engagement of torn towels to effect release of the latch and the tilting of the deflector into operative position, the said deflector being tilted to inoperative position upon the passage of a torn towel thereover, automatic means for resetting the latch upon said tilting of the deflector to inoperative position, and means for limiting the tilting movement of the deflector.
20. In a machine of the class described, the combination with towel feeding means, of normally inoperative means for deflecting towels from their normal path, detector means normally held in position for engagement with the passing towels and operated by the engagement of torn towels to bring the deflecting means into operative position, and means for rendering said detector means inoperative at predetermined times in the operation of the machine.
21. In a machine of the class described, the combination with towel feeding means, of normally inoperative means for deflecting towels from their normal path, detector means normally held in position for engagement with the passing towels and operated by the engagement of torn towels to bring 105 the deflecting means into operative position, and means for moving said detector means from the path of the towels at predetermined times in the operation of the machine.
22. In a machine of the class described, the combination with towel feeding means, of normally inoperative means for deflecting towels from their normal path, detector means normally held in position for engagement with the passing towels and operated by the engagement of torn towels to bring 110 the deflecting means into operative position, and means operating in timed relation with the towel feeding means to periodically move the detector means from the path of the towels.
23. In a machine of the class described, the combination with towel feeding means, of normally inoperative means for deflecting towels from their normal path, detector means normally held in position for engagement with the passing towels and operated by the engagement of torn towels to bring 115 the deflecting means into operative position,

and means operating in timed relation with the towel feeding means to move the detector means from the path of the leading end of the towel and thereafter lower the same 5 onto the towel.

24. In a machine of the class described, the combination with towel feeding means, of a bar engaged by said feeding means for movement through the machine and having connection with the leading ends of the towels, normally inoperative means for deflecting torn towels from their normal path, detector means normally held in position for engagement with the passing towels and operated 10 by the engagement of torn towels to bring the deflecting means into operative position, and means operating in timed relation with the towel feeding means to move the detector means from the path of said bar during 15 the movement of the latter past the same and to thereafter return said detector means into engagement with the towels.

25. In a machine of the class described, the combination with means for feeding towels 25 in flat form, and means for winding said towels into roll form, of a deflector at the rear of the winding means movable to and from an operative position in the path of the rolled towels, detector means positioned in 30 advance of the winding means for engagement with the passing unrolled towels and actuated by the engagement of torn towels, and means operative upon the actuation of 35 the detector means to bring the deflector into operative position.

26. In a machine of the class described, the

combination with means for feeding towels in flat form, and means for winding said towels into roll form, of a deflector at the rear of the winding means movable to and 40 from an operative position in the path of the rolled towels, detector means positioned in advance of the winding means for engagement with the passing unrolled towels and actuated by the engagement of torn towels, 45 and means operative upon the actuation of the detector means to bring the deflector into operative position, the said deflector being automatically returned to its normal inoperative position by the passage of a rolled 50 towel thereover.

27. In a machine of the class described, the combination with means for feeding towels in flat form, and means for winding said towels into roll form, of a pivoted deflector at the rear of the winding means movable to and from an operative position with one end extending into the path of the rolled towels, detector means positioned in 55 advance of the winding means for engagement with the passing unrolled towels and actuated by the engagement of torn towels, and means operative upon the actuation of the detector means to tilt the deflector into 60 operative position, the said deflector being 65 automatically tilted back to its normal inoperative position by the passage of a rolled towel thereover.

In testimony whereof we affix our signatures.

WILLIAM W. TRINKS.
BENJAMIN W. TUCKER
